[57] CLAIM

The ornamental design for an eyeglass holder, as shown and described.

DESCRIPTION

FIG. 1 is a top, front, and right-side perspective view showing my new design;

FIG. 2 is a top plan view thereof;

FIG. 3 is a bottom plan view thereof;

FIG. 4 is a right side elevational view thereof, the left side elevational view being a mirror-image thereof;

FIG. 5 is a front elevational view thereof;

FIG. 6 is a rear elevational view thereof;

FIG. 7 is a top, front, and right-side perspective view showing another embodiment of my new design;

FIG. 8 is a top plan view of FIG. 7;

FIG. 9 is a bottom plan view of FIG. 7;

FIG. 10 is a right side elevational view of FIG. 7, the left side being a mirror image;

FIG. 11 is a front elevational view of FIG. 7; and,

FIG. 12 is a rear elevational view of FIG. 7.
